Berthold A. Lange,
By Hugh H. Wagner,
Atty.

UNITED STATES PATENT OFFICE.

BERTHOLD A. LANGE, OF ST. LOUIS, MISSOURI.

BOX JOINT.

1,415,368.

Specification of Letters Patent. Patented May 9, 1922.

Original application filed May 24, 1920, Serial No. 383,740. Divided and this application filed August 2, 1920. Serial No. 400,625.

To all whom it may concern:

Be it known that I, BERTHOLD A. LANGE, a citizen of the United States, residing at the city of St. Louis, in the State of Missouri, 5 have invented certain new and useful Improvements in Box Joints, of which the following is a specification.

This is a division from, and continuation of, an application filed by me May 24, 1920, 10 Serial 383,740.

The object of this invention is to provide a cheap and speedy means of creasing the pasteboard, fiber-board, strawboard, or the like of which boxes are made at certain lines 15 so that the corners of the box may be quickly and efficiently formed from said creases. To do this dies are brought together by any suitable means, the material being engaged between said dies in such a manner as to form 20 the creases in the said material. Previous to my invention, it has been the practice to form these creases by two or more operations. By the use of my invention it is possible to form any number of such creases at 25 the same time by a continuous operation. It is also possible, with minor changes in the shape of said dies, to form creases of any desired cross-section. It will be understood that the term "corners" as herein used 30 applies to such construction whether in a vertical or horizontal plane, i. e., whether along what are usually called edges or at what are usually called corners.

In the accompanying drawings forming 35 part of this specification, in which like numbers of reference denote like parts wherever they occur,

Figure 1 is an end elevation showing a set 40 of dies with the paste board in position;

Figure 2 is a section taken on the line 2—2 of Figure 1 showing the upper die member in a raised position;

Figure 3 is a similar section showing the die member in a lower position;

Figure 4 is an end elevation of the upper die member;

Figures 5, 6, and 7 are cross-sectional views showing the corner construction of such boxes;

Figure 8 is a fragmental perspective view showing a well-known type of box construction possible with the use of my invention;

Figure 9 is a view of the blank from which the end of a solid-ended box is constructed;

Figure 10 is a view showing the arrange-

ment of dies used in the construction of the end of a solid ended box; and

Figure 11 is a sectional view showing how a plurality of dies may be employed at the same time.

The bed or lower die 1 has an upright guiding box 2 formed thereon. Guide-ways 4 are formed in said box at an angle, as shown in Figures 2 and 3. These guide-ways receive tongues 3 formed upon the ends 65 of the upper or movable die members 5. Upon the bed 1, is a groove or channel 6, as shown in Figures 1, 2, and 3. The paste-board 7 is placed upon the bed 1, as shown in Figure 2. The upper die 5 is then pressed 70 downwardly by any suitable means and an extension 8 on the die 5 forces a portion of the pasteboard 7 into groove 6 on the bed 1. Owing to the action of the guide-ways 4 upon the tongues 3, the die 5 is forced downwardly on the same angle that the guide-ways 4 are formed. This angular movement 75 of the upper die member 5 effectually creases the paste-board at three points, viz: at the point of the groove 6 and at the points designated by the numerals 9 and 10. The die member 5 descends with an appreciable force. This force tends to disarrange the general structure of the paste-board layers or laminations so that after the paste-board 80 has been creased as described it may be easily bent so as to form a crease for said box. Obviously by changing the shape of the die members any desired corner construction 85 may be obtained with this method of creasing. It is possible to put any number of creases in a piece of paste-board in one operation.

Figure 11 shows an arrangement of dies for creasing the paste-board in a plurality 95 of places at once. The bed 1 is extended and includes a plurality of grooves 6. A plurality of dies 5 are mounted as shown with the guiding slots 4 slanting downwardly toward the center 10 of the bed 1 for reasons hereinafter pointed out. As the creasing operation takes up a considerable amount of paste-board, it is necessary to stamp the two creases at 11 and 12 first, then the next two creases at 13 and 14 on either side of the center 10 are stamped. In case more than four creases are desired the operation continues 100 in the same manner. When the two central creases 11 and 12 are formed it results in a movement of the paste-board toward the 110

center 16 of the bed 1, as indicated by the arrows. Obviously, if the creases 13 and 14 were formed at the same time as the creases 11 and 12 it would result in the straining or breaking of the paste-board 7.

In the manufacture of paste-board boxes of the solid-end type, a blank 15, such as shown in Figure 9, is used. It is creased along the dotted line 16, and the flaps 17 are bent upwardly and attached by staples 18 (see Figure 8) to the side walls 19 of the paste-board box. This method of creasing allows these four creases 16 to be put into the blank 15 in one operation. To do this the dies are placed as shown in Figure 10 in uprights 20 mounted upon a rectangular bed 21. The die members 5 are placed at right angles, as shown, and are moved down into the paste-board in pairs so as not to strain said paste-board, as mentioned above.

After the paste-board 7 has been creased as shown in Figures 2 and 3, a corner is formed along said crease, as shown in Figure 5. The excess paste-board on the inner side 25 of the corner extends as at 22 from one side 23 of the box and forms a right angle brace for the adjacent wall 24 of the paste-board box. In using the excess paste-board in this way, the paste-board is prevented from bulging at the outer edge of the corner 25. This permits the boxes to be packed closer together when shipping and gives a stronger box corner.

Obviously, by changing the mounting of the dies 5, any desired shape of paste-board 35 may be creased. With this method of creasing a much greater range is provided. The manufacture of paste-board boxes is by this invention cheapened and the mechanism necessary to form the creases in said boxes 40 is materially reduced.

An additional advantage of the construction herein described over the old form depicted in Figure 7 is that thus formed and braced by the material 22 as shown in Figure 45 5 the edge of the box can not shift.

Having thus described this invention, I hereby reserve the benefit of all changes in form, arrangement, order, or use of parts, as it is evident that many minor changes 50 may be made therein without departing from the spirit of this invention or the scope of the following claims.

I claim:

1. In a device of the character described, 55 a box corner formed along creased lines, a bracing portion formed on the inner side of said corner from the excess paste-board resulting from the forming of said corners.
2. A box joint including a laminated body 60 creased to permit folding at right angles to provide a reinforcing portion along the line of the crease.

In testimony whereof I hereunto affix my signature.

BERTHOLD A. LANGE.
